UNITED STATES PATENT OFFICE.

HOWARD GILMORE, OF BROOKLINE, MASSACHUSETTS.

FILAMENT-SUPPORT.

1,001,135.

Specification of Letters Patent. Patented Aug. 22, 1911.

Application filed January 30, 1911. Serial No. 605,383.

To all whom it may concern:

Be it known that I, HOWARD GILMORE, a citizen of the United States, and resident of Brookline, county of Norfolk, State of Massachusetts, have invented an Improvement in Filament-Supports, of which the following description, in connection with the accompanying drawing, is a specification, like characters on the drawings representing like parts.

The object of this invention is to produce an incandescent electric lamp in which the union or connection between the support for the filament and the glass stem is of such a character as to be maintained without injury to or fracture of the glass during the unequal expansion of the parts due to heat either in the manufacture or use of the lamp.

Incandescent electric lamps, especially those employing the metallic filaments now in common use, require a number of supports for the filament. These supports may simply act to hold the filament at different points in position, or may also serve as conductors for the electricity from the end of one filament to the end of another filament.

It has been common heretofore to use a metal wire for a support and to secure it in position by anchoring it in the glass stem, or a prolongation thereof. This anchoring is usually effected by heating the glass stem to a red heat and forcing the wire support into the molten glass. In the case of smaller sizes of lamp, where the supports and the filaments are light, this is practicable, but in the larger sizes of commercial lamps, particularly such as are used for outdoor or street lamps, it is found very difficult to make a connection of this sort which will be maintained during the temperature changes which take place in subsequent steps in the manufacture of the lamp and in the use of the lamp. All the cheaper metals, such as iron and copper which are used for this purpose, have a much greater coefficient of expansion than that of glass.

The present invention is based upon the principle of so constructing the filament support and so connecting it with the glass stem that upon expansion of the parts the metal of the support will expand away from the glass without cracking or fracturing it, but at the same time maintaining its positioning connection therewith.

The nature of the invention will more

fully appear from the accompanying description and drawings and will be particularly pointed out in the claims.

The drawings show one form of incandescent lamp suitable for street lighting embodying this invention.

In the drawings, Figure 1 is a perspective view of a metallic filament incandescent lamp of a size suitable for out-of-door lighting having the construction of the present invention embodied therein; Fig. 2 is a side elevation of a portion of the prolongation of the glass stem of the lamp in one stage of its manufacture; Fig. 3 is a view similar to Fig. 2 in a second stage of manufacture; Fig. 4 is a view similar to Fig. 3 enlarged and showing the filament supports connected therewith; Fig. 5 is a top plan of the construction shown in Fig. 4.

Incandescent electric lamps such as illustrated in Fig. 1 are well known and comprise the glass bulb 1, the base 2, with its terminals consisting of the disk 3 and the screw-threaded casing 4, and the glass stem 5. In lamps of this character employing metallic filaments the stem 5 is usually prolonged, as shown in the rod 6, and in using the term "stem" herein it is intended to include the entire element made of glass and comprising the base portion or stem proper 5 and the prolongation 6.

The leading-in-wires 7 and 8 are connected to the terminals 3 and 4 and pass out through and are embedded in the stem 5 in the usual manner.

The metallic filament 9 which extends between the terminals 7 and 8 comprises a number of loops and is, therefore, supported at various points. In the form shown in the drawings it is formed into three loops. Each loop at its middle is supported by a wire support 10. These wire supports are not in the circuit and their sole function is simply to hold the loops in position. There being little strain upon them and being formed of light wire and not conducting the current, they may be secured to the stem in the usual and common way by heating the stem red hot and forcing the end of the support into the stem. The free ends of each loop must be so connected, however, that the current may flow therethrough from one terminal 7 to the other terminal 8 and, hence, the supports for the free ends of the loops of the filament must be conductors and, hence, made of comparatively heavy

wire, copper being ordinarily used. In such case, the difficulties already referred to arise and here the present invention comes into play and produces a simple and efficient 5 construction whereby all these difficulties are eliminated.

The filament supports are shown in perspective in Fig. 1 and enlarged in Figs. 4 and 5, and in the preferred form illustrated 10 each support comprises a piece of sheet metal 11 having at one end converging jaw members 12 presenting therebetween a narrow mouthed opening and forming a jaw. The other end of the support 11 is bent 15 back upon itself, as shown at 13, to inclose and lock in position the auxiliary supporting member 14 to the ends of which the loops of filament are mechanically and electrically secured. 20 The sheet metal construction is preferred, because the main supporting members 11 may be cheaply manufactured by punching, and may be bent to secure and hold firmly the auxiliary member 14, but it is only essential 25 that the supporting member, however formed, shall present at one end an opening or cavity having a comparatively narrow mouth.

The prolongation 6 of the stem is heated 30 red hot at the point where the connection is to be made and then by forcing the cooler parts together a thickened portion in the form of a disk 15 results. To this thickened portion the supporting member is then connected. In the lamp illustrated this connection is formed so as to have the plane of 35 the sheet metal supporting member 11 lie transversely of or perpendicular to the stem, but this is obviously not essential. 40 When, however, it is done, as in the present case, the disk 15 is flattened to present the tabs or projections 16 shown in Fig. 3.

In the next step of the operation, and by 45 means of suitable clamps and devices not necessary to describe, the stem 6 is supported and the supporting member 11 is supported relatively thereto so that the tab 16 extends into the opening between the jaw members 12, the member 11 lying in a plane 50 transversely to the stem 6. The glass is then again heated red hot in the vicinity of the tab and when it is red hot the tab 16 is pinched or clamped in the direction of the 55 length of the stem to force the glass into and about the open jaw of the supporting member. This process is repeated with respect to each tab and results in the construction shown enlarged in detail in Figs. 4 and 5, and in which the glass of the stem enters 60 and fills the opening in the jaw of the filament supporting member. The filament supporting member thus substantially surrounds, incloses, and grips a portion of the 65 glass of the stem, and by "substantially" is meant to such an extent that the parts

cannot be separated by reason of the interlocking connection no matter what expansion takes place.

The metal of the filament supporting member has a greater coefficient than that of the 70 glass so that when either during the process of manufacture or in the use of the lamp-expansion takes place the metal of the filament supporting member will expand away from the glass and not into it, thus preventing injurious fractures or cracks, but this expansion, owing to the shape of the parts, is insufficient to destroy their positioning engagement.

It is to be noted that but one form of filament support has been illustrated and described; but it is obvious that the only essential feature of the construction is that this support shall present a cavity or opening which shall engage a portion of the glass of 85 the stem by substantially surrounding and inclosing it, so that when expansion takes place the metal of the filament support may expand away from the glass without becoming disconnected therefrom.

Having fully described my invention what I claim as new and desire to secure by Letters Patent is:

1. An incandescent electric lamp comprising a glass stem, a filament support having a coefficient of expansion greater than that of the glass stem and presenting a gripping head substantially surrounding and gripping a portion of the stem of said head thus firmly securing the filament support in position at all times upon the stem but expanding away from the glass when heated so as not to fracture the glass while remaining engaged therewith.

2. An incandescent electric lamp comprising a glass stem, a filament support having a coefficient of expansion greater than that of the glass stem and presenting an open jaw, a portion of the glass stem extending into said jaw so as to be substantially surrounded and inclosed thereby, the expansion of the parts by heat tending to move the jaw away from the inclosed glass, but not sufficiently to release the parts from positioning engagement.

3. An incandescent electric lamp comprising a glass stem, a sheet metal filament supporting member having at one end converging jaw members presenting therebetween a narrow mouthed opening, a portion of the glass stem extending into said opening so as to be substantially surrounded and inclosed by the jaw members, the expansion of the parts by heat tending to move the jaw members away from the inclosed glass, but not sufficiently to release the parts from positioning engagement.

4. An incandescent electric lamp comprising a glass stem, a sheet metal filament supporting member arranged in a plane per-

pendicular to the stem and having at one end converging jaw members presenting therebetween a narrow mouthed opening, a portion of the glass stem extending into said opening so as to be substantially surrounded and inclosed by the jaw members, the expansion of the parts by heat tending to move the jaw members away from the inclosed glass, but not sufficiently to release the parts from positioning engagement.

5. An incandescent electric lamp comprising a glass stem, a sheet metal filament supporting member having at one end converging jaw members presenting therebetween a 10 narrow mouthed opening, a portion of the glass stem extending into said opening so as

to be substantially surrounded and inclosed by the jaw members, the expansion of the parts by heat tending to move the jaw members away from the inclosed glass, but not 15 sufficiently to release the parts from positioning engagement, an auxiliary supporting member, and means for uniting said supporting members.

In testimony whereof, I have signed my name to this specification, in the presence of two subscribing witnesses.

HOWARD GILMORE.
